LOOM WEIGHTING FOR WEAVING

Henry Richmond, Great Lever, Bolton, England

Application July 14, 1949, Serial No. 104,761
In Great Britain February 12, 1949

3 Claims. (Cl. 139—100)

1

The invention relates to an improved let-off motion for cloth weaving.

This invention aims at dispensing entirely with the necessity of the weaver lifting the heavy loom weights placed upon the beam to tension the yarn.

In principle the motion eliminates the heavy weights placed on the weight levers at the back of the loom, used for applying tension to the warp or weavers beam and which call for frequent alteration of position of the weights, as the beam decreases in diameter. The lifting of the heavy loom weights often caused weavers to strain or rupture themselves. This invention applies compression springs of almost any strength (the strength regulated by the style of cloth being woven), to produce a standard rate of tension during weaving, and at all warp diameters. The motion can briefly be described by examining the centre box or casing. In this box are housed two compression springs. These are placed upon two screw threaded bars. The bars are pushed through the holes bored in the box and the screw threaded ends of the bars are screwed into blocks, of which there are two, one for each bar. At the outer end of each bar a hook is made.

As these bars are pulled it will be seen that the blocks are drawn outward and the compression springs are drawn against the ends of the box by the screw threaded bars, thus anything linked to these bars receives the whole of the force of the compression springs.

The blocks slide very freely in the metal box or casing, and in operation they are urged toward each other by the springs and thus the requisite tension or drag is transmitted to the warp beam through the levers and chains which are coupled to the warp beam.

Short bars having loops on their inner ends engage with the hooks of the spring bars and are secured to side levers which are fastened to the loom sides. On each of the short bars a coarse or buttress screw thread is cut, this allows for a small wheel of four inches in diameter to work or turn on the small bar. It will be seen that as the wheel is turned, it either moves inward or outward and through the connection to the levers, controlled pressure is transmitted to the warp beam. Through the side levers, screw headed hooks are placed and are hooked on to the warp beam chains. Small wheels are screw threaded onto these hooks and act as nuts to tighten up the connection between the beam chains and the side levers, thus placing more or less pull or tension on the beam through the compression springs.

2

In the centre of the casing a shaped cam is fitted for the purpose of compressing the springs and so slackening off the tension on the beam. This shaped cam swivels on a centre stud. In order to make it easy for the weaver to slacken off the springs, a foot rest or table is fixed to the centre stud. When the weaver wishes to slacken off the beam, foot pressure on this foot rest turns the cam horizontally and this in turn pushes the spring loaded blocks outwardly and so slackens the chains on the beam ruffles, thus easing the tension on the beam. The warp beam is allowed to move backwards and forwards, the give and take of the compression springs allowing for this. Compression springs of any strength may be used in this invention in order to increase or decrease the amount of pressure required to be exerted on the beam.

The invention is illustrated somewhat diagrammatically, and by way of example in the accompanying drawing, in which—

Figure 1 is an elevational view of one construction.

Figure 2 is a view similar to Fig. 1 with the motion out of action, through the compression springs 13 being at rest.

Figure 3 is a detail view of one of the levers 5 linking the motion with the beam.

Figure 4 is a detail view, partly in section, illustrating the centre cam 8, also blocks 3 and compression springs 13.

Behind the loom and fixed to the centre of the back rail of the loom is an oblong or cylindrical box or casing 1 shown in Figures 1 and 2. On this casing at each end is bored one hole, through these holes two slide bars 2 are inserted at opposite ends to each other. These bars are each screw threaded at one end for the purpose of enabling them to be screwed into two blocks 3 facing each other. On these bars strong spiral springs 13 are placed and when the bars are pulled outward, the blocks 3 move along with them. This causes the springs to be slightly compressed, thus giving a pull to the bars 4 and levers 5 which are linked to the warp beam.

The outer end of each slide bar 2 is made with a hook for the purpose of engaging with another bar 4. This second bar is made with a loop at one end; this loop end is hooked on to the bar 2 and the bar 4 is in turn fixed to one of the levers 5 bolted to the side of the loom. The latter bar has a coarse screw thread cut into it on the buttress principle, which allows for a small wheel 6 four inches in diameter, which has been threaded so that it can turn on the thread

of bar 4. This allows for the drawing together or slackening off of the bars 4, which carries through to the compression springs 13 through the bars 2. It will be seen that pressure is put on the warp beam or taken off by the compression springs 13 and levers 5. The bars are connected to the side levers 5 through a round nut 12, which is swivelly connected to the wheel 6. This nut 12 fits into a claw or slotted position of the levers 5 at 15. This enables the springs 13 to be adjustably compressed. For the purpose of connecting the motion to the warp beam, the beam chains, which are around the ruffles of the beam, are connected to hooks 7, about six inches long. These hooks 7, are screw threaded with a coarse screw thread and are placed one at each side of the loom. The hook portion is placed into one of the holes or links of the chain. On this threaded hook a small wheel 10 is screw threaded with similar thread to the hook. This small wheel 10 serves the purpose of a nut and, by turning in the right direction, tightens up the chain and brings the motion into its correct position for adding pressure to the beam. In the centre of the box or casing 1 a cam 8 is secured on a stud or small shaft at 14 which allows for the slackening of the compression springs 13 when the weaver requires the beam to be slackened off. The cam 8 is bored in the centre and a small arm or lever is fitted into it and a foot rest or turn table arrangement 9 is fixed to the small arm by set screws or keyed on to it. When the foot rest or table 9 is depressed the cam 8 turns to a horizontal position, this cam then slides between the two blocks 3. By this means the springs are compressed slightly and this allows the chains on the warp beam to be slackened and in position for the turning back of the beam. At 11 a small plate is fixed which comes in contact with the floor and prevents the cam 8 from getting out of its horizontal position.

Having now particularly described and ascertained the nature of my said invention, and in what manner the same is to be performed, I declare, that what I claim is:

5 1. In a loom having a warp beam, a warp let-off comprising: a casing secured to said loom, two opposed blocks slidably mounted in said casing, a hook bar secured to each block and extending outwardly from said casing in opposite directions, compression springs on said bars between said blocks and the ends of said casing for normally urging said blocks towards each other, means connecting said hook bars with the ends of said beam to transmit braking pressure from said springs to said beam and means for moving said blocks away from each other to relieve said braking pressure.

20 2. The combination according to claim 1 in which the connecting means comprises bars connected to said hook bars, levers mounted on said loom and adjustably connecting said levers to said warp beam.

25 3. The combination according to claim 2 in which the relieving means comprises a cam pivotally mounted in said casing between said blocks and means connected to said cam for moving the same.

HENRY RICHMOND.
